ABSTRACT: Adapted for use drilling steep or horizontal rock faces. A hydraulic cylinder assembly with upper and lower piston rods extending through upper and lower cylinder heads, the piston rods being secured in a piston. A lower end of the lower piston rod is anchored through universal joint to a rock face being drilled, the upper end of the piston rod being secured at an apex of a tripod. The drill is attached to the cylinder with a longitudinal axis of the drill parallel to a longitudinal axis of the cylinder assembly. Provision for admitting water under pressure to an upper cylinder space with a lower cylinder space being connected to a bleeder pipe having a bleeder valve. With the bleeder valve opened a small amount, the drill is fed downwards against the face at a rate which is a function of the amount by which the bleeder valve is opened. The cylinder is moved upwards with respect to the piston rods by similarly introducing water under pressure to an upper cylinder space, so that the hydraulic cylinder also provides means of pulling a drill rod from the hole. Water supply from source used to lubricate and cool the drill.

DRILL-SUPPORTING APPARATUS

RELATED APPLICATION

This is a continuation-in-part of our copending application Ser. No. 813,134 filed 3 Apr. 1969 and now abandoned.

FIELD OF THE INVENTION

The invention relates to apparatus for supporting for instance a diamond drill in operating position, and for providing automatic feed. While the apparatus is particularly suitable for use with small portable drills, it is adapted for use with large drills.

PRIOR ART

During drilling, a force is applied urging a drill bit against a face, usually rock face, in which a test hole is being drilled. The should be axial, and longitudinal motion of the drill penetrating the face should be essentially axial translation.

Means are also required to feed the drill. In a manual drill press commonly used in a machine shop, the press provides a mechanism restraining travel of the drill as above, a machinist applies the force and effects the feed by means of a lever. Ordinarily homogeneous material is being drilled in a machine shop, and mechanism to effect automatic feed can be relatively simple.

Means to maintain alignment and effect feed of a diamond drill are known.

Some manual versions of devices used in portable rock drills use a lever to apply force to the drill and to effect feed, being in this respect analogous to a manual drill press of a machine shop. This involves heavy work, and the drill can be advanced through but a short distance before repositioning of the lever is required so that drilling can be continued. As the hole deepens so that an additional length of the drill rod is required to be added, the drill and lever are disconnected so that the additional bit drill length can be added. This too is heavy work, and alignment is a problem particularly in initial stages of the drilling. Automatic devices with power feed as known to the present inventor are expensive and heavy, and thus are not ordinarily practical for use with small portable drills.

SUMMARY OF THE INVENTION

The present invention is directed to reduce difficulties and disadvantages of manual and power drill apparatus known to the present inventors, and to provide simple cheap automatic apparatus powered by fluid pressure of a water supply. Water at suitable pressure is ordinarily available, being used to lubricate and to clean out a diamond drill test hole.

Apparatus according to the present invention provides a double acting hydraulic cylinder having an upper piston rod extending through an upper cylinder head, and a lower piston rod extending through a lower piston head, inner ends of the piston rods being secured in a piston. A lower end of the lower piston rod terminates in a universal joint, a stub shaft of which is anchored in the rock face. An upper end of the upper piston rod is secured at an apex of a supporting means, such as a simple tripod.

A guide rod is secured externally to the cylinder parallel to a common axis of the cylinder the piston and the rods. The drill is mounted on the guide rod with the drill rod parallel to the common axis, means being provided for the drill to be movable upwards and downwards of the guide rod, or intermediate. It is seen that the universal and the tripod thus provide means to orient the drill rod in a direction according to that in which the hole is to be drilled.

Water is used, as has been explained for lubricating the drill and flushing the drill hole, hence a supply of water under pressure is available.

A selector valve can selectively be set in position as follows: up, to direct water under pressure to an upper cylinder space between the piston and the upper cylinder head, with a lower cylinder space defined between the piston and the lower

cylinder head being connected to a bleeder pipe discharging to atmosphere through a manually controlled valve; in a down position water under pressure is directed to the lower cylinder space with the upper cylinder space then being connected to the bleeder pipe; and in an off position at which all valve ports are closed.

Both cylinder spaces being charged with water, it is seen that setting the valve to admit water to pressurize to the lower cylinder space will not cause the cylinder to move if the bleeder valve is closed. Consequently, with the valve so positioned, opening of the bleeder valve by a slight amount causes the cylinder, and with it the drill and the drill rod, to move downward at a rate according to the amount by which the bleeder valve is open. It is seen that nice control of feed at a rate according to the opening of the bleeder valve is thus effected, the force applied to the drill rod urging it downwards depends upon resistance encountered by the drill—this depends upon rate of feed and upon the material—and can attain

10 a maximum equal to supply pressure available at the valve times piston area, the maximum being approached as the drill rod approaches stall—when the available force is insufficient to continue to advance the drill. Maximum rate of feed varies directly as available flow rate, and inversely as the piston area.

15 25 Hereinafter unless otherwise stated, "supply pressure" means pressure available at the selector valve, viz pressure at the pump, less line and leakage loss, and less any pressure drop resulting from use of the water in the drill. When the drill is secured to the guide rod in a fixed portion, it is locked against the guide rod, and rotation of the cylinder about the piston is restrained by large cup seals mounted on opposite faces of the piston. The cup seals are of resilient material so as to be expanded outwards by the pressure within the cylinder 30 spaces, thus restraining the cylinder from rotation about the common axis.

35 Structure as above provides means to apply force urging the drill rod downwards against the face, an equal and opposite force arising at the anchor. These forces are parallel producing a first moment, the structure providing means to apply an equal and opposite restraining moment. Means are also provided to effect control of feed of the drill rod, the apparatus being constructed and arranged to effect that feed of the drill rod is essentially axial motion of translation at a determinate rate, maintaining alignment as the drilling progresses. The structure also provides means to pull the drill rod from the hole.

40 45 A detail description following related to drawings gives exemplification of structure according to the present invention which, however, can be expressed by means other than those particularly described and illustrated.

DESCRIPTION OF THE DRAWINGS

50 55 FIG. 1 is an elevation of apparatus according to the invention, shown with a conventional portable diamond drill,

FIG. 2 is a large scale plan of a part of the apparatus as seen from 2—2 FIG. 1,

60 FIG. 3 is a fragmented detail elevation showing a fluid cylinder assembly, the drill, and a part of a tripod,

FIG. 3A is a plan showing structure at an apex of the tripod as seen from 3A—3A, FIG. 3,

65 FIG. 4 is a fragmented section through the fluid cylinder showing an anchor means, some parts not being shown in section,

FIG. 5 is a fragmented partly sectioned detail elevation of a portion of the cylinder showing mounting means for the drill,

FIG. 6 is a fragmented side elevation of a rod-pulling means,

70 FIG. 7 is a section on 7—7 FIG. 6,

FIG. 8 is a force diagram showing forces on the fluid cylinder assembly and drill,

FIG. 9 is a top plan detail of an alternative collar construction,

75 FIG. 10 is an elevation of the collar shown in FIG. 9.

DETAILED DESCRIPTION

The portable drill, FIGS. 1 and 3

The portable diamond drill designated generally 10 in FIG. 1 is driven by an internal combustion engine 11. The drill has a tubular drive shaft 12 which is threaded to accept a drill rod 14, having a longitudinal axis designated 14.1 in FIG. 3 only. The drill rod made up of lengths of hollow drill rod 15, screwed together at joints 16. A diamond drill bit 17, FIG. 3 only, is secured to a lower end of the drill rod.

Water for flushing and cooling enters the drill through a pressure hose 18 from a pump 19 drawing water from a source, not shown. The water, which is typically at 50 to 100 pounds pressure, passes through the shaft 12 and the hollow drill rod 14, cooling the bit and flushing material away from a bottom face of a hole been drilled. The pump 19 is of a type other than positive displacement, e.g., centrifugal.

Portable diamond drills of this kind are well known, further details of construction, and of operation except as directly related to the instant apparatus, are not deemed to be necessary.

Drill supporting apparatus, FIGS. 1 and 4, fluid cylinder assembly and tripod

In FIG. 1 the drill-supporting apparatus generally 20, is shown holding the drill 10 in position for drilling a test hole 23 in a generally horizontal rock face 22. The supporting apparatus includes support means, viz a tripod 24 having a apex 24.1, and a double-acting fluid cylinder assembly 25 a piston rod of which is secured at the apex, the apparatus feeding the drill rod and maintaining alignment as drilling progresses, and also withdrawing the drill rod from the test hole.

Referring particularly to FIG. 4, the cylinder assembly 25 has a double-acting cylinder 25.1 having a piston 26, aligned upper and lower piston rods 27A, and 27B secured in opposite faces of the piston 26 and being extensible and retractable through upper and lower cylinder heads 28 and 29 providing a range of motion of the cylinder relative to the piston between upper and lower limits. The cylinder and piston rods have a common axis 30, the rods passing through pressure bushes 31 and 31.1.

An upper cup seal 32 has a base 32.1 and a sidewall 32.2, the base being secured to an upper face of the piston 26 so as to be concave upwards as shown. A lower cup seal 33 has a base 33.1 and a sidewall 33.2, the base being secured against a lower face of the piston 26 so as to be concave downwards as shown, both cup seals being of known flexible material. Means generally 36 anchor a lower end of the lower piston rod in the face.

Anchor means, FIG. 4.

A universal joint 38 has a lower stub shaft 39, a lower end of the lower piston rod 27B being secured in the universal joint as seen at 40. A hole 42 is drilled in the face 22, the hole having a depth and diameter to accept the stub shaft 39. A wedge 43 driven as shown forces the stub shaft 39 against a sidewall of the hole 42, securing the shaft in the hole. To provide increased bearing area of the wedge against the shaft, the wedge can have an inner face 43.1 conforming to the shaft.

Structure at the apex of the tripod, FIGS. 3 and 3A

The tripod 24 has legs 44, 45, 46, all three legs appearing in FIGS. 3A only. Upper ends of the tripod legs are secured by ball and socket means 47, 48, 49, in a collar 53 at the apex 24.1, the collar having an inside diameter to accept the upper piston rod 27A sliding therethrough. Upper and lower adjustable stops 55 and 56 are moveable upwards and downwards of the piston rod 27A being securable in an adjusted position by tightening screws 57 and 58 respectively. The upper stop 55 can be placed to bear against an upper end wall 59 of the collar 53, so that downward movement of the piston rod 27A is stopped, resisted by compressive reactions in the legs. The stop 55 is shown so positioned in FIG. 1 only. Structure as above, designated generally 60, and alternative later described, is means to secure the upper piston rod at the apex of the tripod.

Fluid circuit, FIGS. 1 and 3

Referring to FIGS. 1 and 3, control means generally 62 includes a four-way selector valve 63 secured by a bracket 65 to the cylinder 25.1, the valve being operated by a lever 66.

5 A pressure hose 68 is connected to a junction 67 of the pressure hose 18 so that fluid, namely water under pressure from the pump 19, enters the pressure hose 68 being an intake hose of the four-way valve 63. Discharge hoses 69 and 70 lead respectively to the upper and lower cylinder spaces 34, 35 (FIG. 4) a bleeder pipe 72 having a bleeder valve 73 operated by hand wheel 74 being provided. The four-way valve 63 is of a common type obtainable from ordinary trade sources and the lever 66 can be selectively set in positions as follows: up, to direct the fluid under pressure through the hose 69 to the upper cylinder space 34, the hose 70 from the lower cylinder space 35 being connected to the bleeder pipe 72; down, to direct the fluid under pressure to the lower cylinder space 35 with the upper cylinder space then being connected to the bleeder pipe, off at which all valve ports are closed.

20 A manual relief valve 75 FIG. 1, close to the pump is to relieve a head which might exist in the hose 18 when the pump is at an elevation much below the drill. The valve 75 discharges to atmosphere through an outlet 76, and can be opened to facilitate starting the pump.

25 Connection of the drill to the cylinder assembly, FIGS. 2, 3, and 5.

The drill is secured to the cylinder assembly by means generally 80 with the drill rod axis 14.1 maintained parallel to the piston rod axis through out a range of vertical travel of the drill relative to the cylinder, the drill rod moving axially through the range of travel. The foregoing is effected by means including a guide rod 81 having spaced holes centerlines of which are aligned in a radial plane through the longitudinal axis of the rod, two such holes designated 82 and 82.1 being shown in FIG. 5. A longitudinal groove 83 extends between the holes, the groove having a depth materially less than that of the holes. A bracket 84, secured to the cylinder 25.1 carries a sleeve 85 having an inside diameter such as to accept the rod 81 sliding therewithin. A holder 86 contains a detent 87 urged outwards by a compression spring 88 so that the detent engages the hole 82 when detent and hole are in register and extending outwards so as to be engaged by a sidewall of the groove 83 when the drill is moved axially. A latch pin 89 secured to the detent is movable within a latch slot 90 so that the detent can be latched out of engagement with the hole. Referring to FIG. 1, it is seen that the drill can be moved upwards and downwards of the rod 81 and locked in a selected position with respect to the cylinder by engagement of the detent 87 in one of the spaced holes such as 82 FIG. 5, the drill rod axis being maintained parallel to the piston rod axis.

40 50 Cup seal action, FIGS. 3 and 4

55 The system being full with the selector valve 63 in the off position the cylinder cannot be moved up or down by an external force, and rotation will be resisted since both the cup seals 32 and 33 FIG. 4 are expanded until or unless pressure leaks off through the bushes 31 and 31.1.

60 65 When the lever is up and the bleeder valve 73 open, with essentially no resistance to motion of the cylinder, pressure in the cylinder spaces is much below supply pressure in the cylinder spaces is much below supply pressure hence the cup seals are only slightly expanded, thus the cylinder can be rotated so as, for instance, to swing the drill to facilitate adding a rod length, and for subsequent alignment. During drilling pressure builds up because of resistance encountered by the drill in penetrating the face, and can approach supply pressure. Hence during drilling the cup seals expanded,

70 75 restraining rotation. As the drill rod axis 14.1 is maintained parallel to the piston rod axis, viz the common axis 30, and rotation of the drill rod about the piston rod axis is restrained, the apparatus provides means to effect that downward motion of the drill rod penetrating the face is axial translation.

75 Rod-pulling means, FIGS. 3, 6, and 7

The apparatus 20 is provided with means generally 100 to pull the drill rod 14 from a test hole. The rod-pulling means 100 includes a pulley 101 which is mounted on a spindle 102 secured to the upper cylinder head 28. The universal joint 38 has an outwardly projecting bracket 104 having an open eye 105 adapted to receive a ferrule. A cable 108 has one end terminated in an eye 106, an opposite end having a ferrule 109 for attachment of the cable in the eye 105.

The rod-pulling means 100 includes wedge clamp means generally 114 (FIG. 7) having a U-shaped fitting 115, a pivot pin bolt passing through spaced opposite arms 117 of the U. A lever 118 is journaled on the bolt 116 the lever having an eccentric cam 119 at an inner end, the outer end of the lever 118 having a ring 120 in which the cable hook 110 is securable.

To prepare for rod pulling after drilling has stopped, the four-way valve 63 is moved to the up position and the bleeder valve 73 is slightly opened to relieve the downward force, and the drive shaft 12 is disconnected from the drill rod 14. When pressure in the cylinder spaces is relieved, as explained, the cylinder can be rotated about the piston 26. The cylinder is then rotated, the drive shaft 12 is moved clear of the drill rod 14, and the pulley 10 is positioned above and alongside the drill rod as best seen in FIG. 7. The ferrule 109 of the cable 108 is attached to the universal joint 38 by engaging the ferrule 109 in the open eye 105 that is to say is secured in a fixed position, and the cable is trained over the pulley 101 with the hook 110 freely suspended. The wedge clamp 114 is slipped over the top of the drill rod 14, and the cable hook 110 is attached to the lever 118 by engaging the hook 110 in the ring 120. At this time the lever 118 is downwardly inclined as shown in FIG. 6 with the eccentric 119 disengaged from the drill rod 14.

The lever 66 of the four-way valve 63 is then positioned to open the valve and allow water under pressure to enter the upper cylinder space 34 thus raising the cylinder. With initial movement of the cylinder upwards, clamping occurs from rotation of the lever 118, and further upward movement of the cylinder causes the cable 118 to pull the drill rod upwards through a distance twice that through which the cylinder moves. When the cylinder is lowered, the eccentric can releases and the clamp drops downward to a new position. The cylinder 25 is moved alternatively upward and downward each time the cylinder is at its lowest position the eccentric 119 takes a new grip on the drill rod 14 so that the rod is progressively pulled from the test hole.

In this way drill rod pulling is accomplished by one operator without need of auxiliary equipment commonly used to extract a buried drill rod.

The apparatus above described serves to support and feed a portable diamond drill and, in addition, provides power needed to remove a drill rod from a test hole. The several parts of the apparatus can be dismantled to form a bundle of a size suitable for shipping into a drilling site by helicopter, by packhorse, or by back-packing. The apparatus utilizes power available for the normal operation of a portable diamond drill viz, pressure supplied by the pump which delivers cooling and cleanout water to the drill bit.

OPERATION

Drilling

In carrying out a drilling operation, the hole 42 FIGS. 1 and 4 is drilled, and the universal stub shaft 39 is wedged securely in the hole. It is seen that alignment of the drill axis 14.1 is parallel to that of the piston axis 30 and, because of the universal 38, is independent of direction in which the hole 42 for the anchor is drilled.

Before assembling the tripod to the piston rod, the lever 66 of the four-way control valve 63 is operated so as to move the cylinder 25.1 FIG. 3 downwards, the upper stop 55 is removed, and the lower stop 56 is loosened. The collar 53 of the tripod is now assembled to the upper piston rod 27A, and the tripod legs positioned so that the lower piston rod 27B is

orientated in a direction according to that in which the test hole 23 is to be drilled. The lower stop 56 can be fixed in a convenient position so as to limit downward movement of the collar. The tripod legs have pointed ends 121 FIG. 1 so as to minimize tendency to slip. When the legs are properly positioned, the upper stop 55 is replaced, and slid towards on the piston rod 27A against the upper end wall 59, FIG. 3, of the collar 53 and the screw 57 is tightened securing the stop in position.

- 10 The drill is now assembled to the guide rod 81 and a single length of drill rod inserted in the hollow drive shaft 12, with the bit 17 installed at the lower end of the rod. A short rod length is ordinarily used as a first length. The drill 10 is positioned near the lower end of the cylinder 25.1 so that the short length of drill rod can be used to start the test hole 23, with initial drilling to a depth of a few inches to serve as a pilot hole. The lever 66 of the four-way selector valve 63 is moved from the closed position to the down position to admit fluid to the 15 lower cylinder space 24. This causes the cylinder and drill to move downward toward the face 22 and, with the engine running, initial drilling commences. Feed is regulated as later described.

- When the pilot hole is sufficiently deep the drill is 20 withdrawn as previously described to provide space for insertion of a drill rod 15 of normal length. It has been explained that the cylinder 25.1 can be swung about the piston rod so that the drill rod 15 can be swung in register with the initial part of the hole already drilled. With the bleeder valve 73 closed, the lever 66 is moved to admit water under pressure to the lower cylinder spaces, pressurization as above causes the sidewalls of both cup seals to be expanded against the inner surface of the cylinder so as to effect locking against rotation of the cylinder with respect to the piston and piston rods. With 25 the lever 66 remaining in the position above, that is to say delivering pressure to the lower cylinder space 35, the bleeder valve 73 is opened by a small amount to allow some of the water present in the upper cylinder space to bleed off and discharge through the pipe 72. Since water under pressure is 30 still being directed to the lower cylinder space 35, the bleeding off of water from the upper cylinder space causes the cylinder 25.1, and with it the drill, to move downwards so feeding the drill at a speed dependent upon the amount by which the bleeder valve is open. It is seen that directing fluid, i.e., water under pressure, to the lower cylinder space and bleeding off as above described provides means to effect nice control of feed, feed of the drill rod being a function of the amount by which the bleeder valve is opened increasing within increase of bleeding, and being decreased with decrease of bleeding.

- 35 50 Rate of feed is adjusted according to the experience of the operator to what he judges to be optimum for the type of rock being drilled. It is to be noted that rate of feed is determined by rate of bleeding, that is to say by the amount by which the valve 73 is opened. If the drill strikes a fissure or soft spot it does not drop suddenly, but continues to advance at the determinate rate above. This is of advantage in reducing damage which can and does result in these circumstances. Some air lock can occur, for instance in the cup seal 33, hence in entering 55 a fissure the drill can advance a short distance at a speed greater than the feed above.

- As the drilling progresses, the piston 26 approaches the end of its stroke whereupon the motor 11 is stopped, the detent 87 is disengaged and the control valve is operated to raise the 60 cylinder 25 towards the upper end of its stroke until the detent 87 is reengaged in a nearest higher hole 82 the groove 83 facilitating reengagement. Drilling is now continued until an upper end of the first length of pipe 15 is just above the face 22. The drill rod is now disconnected from the drive shaft and 65 the drill raised, as before described, to a position for attachment of a second length of drill rod to the drive shaft and to the first length of drill pipe. Drilling can now be resumed. It is to be noted that lifting of the drill after disconnection of the rod is effected by water pressure, and that an entire drilling 70 operation can thus be carried out by one operator since man-

handling is limited to attaching the drill rod length and maneuvering the drill into position.

Forces on the drill and supporting structure, FIG. 1

With the drill being fed into the hole, as described, there is an upward reaction upon the drill rod. This is resisted by a downward pull on the piston rod 27B, see FIG. 1, which downward pull is exerted by the anchor means 36 through the universal 38.

These two forces being equal and opposite produce a couple. Restraint is effected by (at least) one tripod leg in compression resulting in an upward force against the collar 53, exerted by a leg in compression, the upward force on the collar having a vertical component upwards, and a horizontal component. The horizontal component together with an equal and opposite horizontal reaction at the anchor means provides a contrary movement and the upward force component at the collar is added to downward force required to be exerted by the anchor, since the downward force on the collar tends to drive the tripod leg downwards.

If the upper stop 52 is not initially placed against the upper end wall 59 of the collar, it is seen that undesirable bending moment can be introduced causing the drill to tend to travel downwards other than in a straight line and, in an extreme case, causing breakage or other damage.

When the first few inches of initial drilling has been completed, before attaching the full length of drill rod check is to be made that the clamp 55 is still in contact with the end wall 59. It is seen that, stress having been removed, initial settling of the tripod leg will show as space between the end wall of the collar and the upper stop 55. At this time, and before recommencing drilling, any required adjustment of the position of the stop 55 is to be effected. It is prudent to effect a similar check after at least the first upwards repositioning of the cylinder.

Force diagram, FIG. 8

For conditions illustrated in FIG. 1 and neglecting torsion on the drill, there is an upward reaction R on the drill bit 17 in an axial direction and an equal and opposite force V exerted by resistance of the anchor means 36 from being pulled out of the hole in which it is wedged. These equal and opposite forces, which are parallel, produce a couple having a first moment M-1, clockwise as seen in FIG. 8.

The moment M-1 is resisted by an equal and opposite restraining moment M-2 as shown, arising from a force F considered as being applied by the leg 45 FIG. 1—the force being axial of the leg—against the stop 55. The force F is shown in broken outline and having a component h normal to the piston rod axis, and an axial component v. Effectively, the stop can be considered as being in a broken outline position 45.1 where the leg 45 produced would intersect the upper piston rod 27A. With 55.1 being at a height H above the face 22, and with the drill rod 14 being spaced from the piston rod 27A by a distance D, taking moments about the universal 38 we have the first moment M-1 of magnitude RD plus the opposite restraining moment h, H equal to zero, whence

$$h = R \times D / H$$

Typically D/H might be say ten, consequently h typically would be equal to R/10. The leg 45, and consequently the force F, is ordinarily at an acute angle to the piston rod, so that the component v acting on the effective stop 55.1 is ordinarily rather larger than h. Total downward force at the anchor means 36 is thus V+v', where v' is a reaction equal and opposite to v'.

The component h at the stop is balanced by an equal and opposite force h' at the universal 38, applied by the wedge means 36. It is to be noted that the tripod leg 45 is effectively pin jointed at its lower end 121 (FIG. 1) and compressive load cannot be applied to the leg until or unless, see FIG. 3, the upper end wall of the collar 53 comes into contact with the upper stop 55. Consequently, the anchor having a universal joint, undesirable bending stress can arise in the drill rod when it has penetrated to any considerable depth. Bending stress can so arise particularly from play between the collar and the

upper stop, or from reflection of the leg 45 considered as a long column, or from slippage at the lower end 121 of a leg. A possible position of the drill rod 14 under these conditions is shown (in an exaggerated amount) in broken outline at 14.1. In the broken outline position the drill rod 14.1 is straight when there has been little penetration of the bit, and is curved as a strained cantilever when the bit has penetrated a material distance. It is seen then that having the stop 55 adjustable for position as described gives opportunity for the lower end of the tripod leg 55 to find firm footing, and to effect adjustment for any creep which might occur as the drilling progresses—so providing means to maintain the drill rod 14 essentially parallel to the piston rod during drilling, that is to say providing means to effect that feed of the drill rod is essentially axial motion of translation at a rate—according to, as explained above, rate of bleeding.

The reaction R is equal to the force exerted by the drill rod urging the bit against the bottom face of the test hole. It approaches a maximum equal to water pressure times piston area when, or if, this force is insufficient to cause the bit to continue to penetrate the bottom face, so that it stalls. Under these conditions with the bleeder valve 73 wide open, rate of bleeding approaches zero as stalling is approached. While bleeding rate is a linear junction of feed rate, the bleeder valve controls feed in a manner analogous to control of speed of a car by throttle, speed of the car and feed of the drill depend upon power and load as well as upon throttle, or bleeder valve, opening.

30 In pulling the drill rod, directions of forces and reactions shown in FIG. 8 are reversed. A moment still arises as M-1 but of opposite direction, and a corresponding restraining moment as M-2 has an opposite direction.

35 ALTERNATIVE COLLAR CONSTRUCTION

FIGS. 9 and 10

Referring to FIGS. 9 and 10, an alternative collar assembly generally 30 has lugs 131 and 132 extending radially outwards and spaced at 120° as shown. The collar assembly has a hollow cylindrical body 134 with which the lugs 135 are effectively integral, the body having a lower portion 135 of reduced diameter defining a collar 136. A short hollow cylindrical sleeve 137 has an inside diameter to accept the reduced diameter portion 135 so as to be rotatable thereon. The sleeve 137 has an upturned lug 138 having a bore 139 as shown, the lugs 131 and 132 having corresponding bores 141 and 142 circumferentially aligned with the bore 139, as shown. The lug 138 is adapted to receive a fixture 143 (shown in FIG. 9 only) threaded at an outer end as shown at 144, to receive a leg which can be drill rod lengths. The body 134 has an upper end wall 145 adapted to bear against the upper stop 55 as previously described.

Means such as the fixture 143 are capable of rotation with respect to the collar in a vertical plane—the piston rod being considered to be vertical. Since the collar assembly 130 is rotatable about the piston rod, and can also slide up and down the piston rod, there is a range of adjustment to obtain a suitable position for the lower end of one tripod leg. Once the lower end of a leg attached, for instance, to the lug 131 has been positioned, this restricts available range of position for the lower end of a tripod leg attached to the lug 132. A ball-and-socket arrangement, as previously described, can be used for attachment of a leg to the lug 132, the ball and socket giving a greater choice of positions for the lower end of the leg, under a condition as above. It is seen that the sleeve 137 permits the leg attached to its lug 138 to be rotated to a suitable position, notwithstanding another leg or legs have already been positioned. A ball-and-socket joint can alternatively be used here to give a greater range.

The tripod construction shown in FIG. 1 can be used drilling faces which are not horizontal. It is seen that with a steep face approaching the vertical when the anchor means has been secured, adequate restraint can sometimes be effected using

only two tripod legs. Working on an irregular face, particularly a steep face, the collar alternative 130 can be of particular advantage.

The collar 53 FIG. 3 with universally jointed legs, the collar 130 FIG. 9 and 10 with one leg independently rotatable and attachment means such that each leg rotated in a plane containing the axis of the piston rod, a collar embodiment having legs attached by means such as the means 143 FIG. 9 but otherwise similar to the collar 53, and a collar embodiment as FIGS. 9 and 10 with at least one leg being secured by ball and socket means, are all, see FIG. 8, means to apply a restraining moment M-2 to counteract the moment M-1 arising from drill bit anchor means reaction as explained, and provide structure alternative to that described with reference to the means 60 FIG. 3.

FURTHER CONSIDERATIONS

The detail description has been related to a drill driven by an internal combustion engine. In underground workings, a fluid motor would be used to drive the drill. Conditions determining rate of feed of the drill, and maximum force urging the drill against the face, have been stated prior to the detail description. With structure as exemplified in the detail description, these limits are apparent it being understood that, by supply pressure, is meant pressure available at the valve 63. While a positive displacement pump could be used, to do so involves difficulty. Centrifugal pump supply, or gravity supply, avoids such difficulty.

Referring to the guide rod 81 FIG. 3, it is seen that the rod extends beyond each end of the cylinder 25.1 and thus can have a length of, say, twice the range of motion, or stroke, of the cylinder with respect to the piston. Drilling being commenced with the drill at a position near the upper end of the guide rod, when the drilling has continued for the length of the stroke the drill can be repositioned at intermediately of the guide rod so as to sink the drill further. Repositioning near the lower end of the guide rod enables a drill rod of standard length to be buried, notwithstanding the cylinder has a stroke much less than the length of the drill rod—as exemplified above the stroke is about one-third of the length of a standard rod. Thus the cylinder can be relatively small. In FIG. 1 the drill is shown repositioning near the lower end of the guide rod, with the cylinder having commenced its downward stroke.

We claim:

1. An apparatus for supporting a drill the apparatus including a drill rod 14 having a longitudinal axis 14.1, the apparatus feeding the drill and maintaining alignment as drilling of a face progresses; the apparatus including,

a. means 25 to apply a force urging the drill rod 14 against the face being drilled, the force having a reaction R FIG. 8,
b. means 36 to apply an opposite force V equal in magnitude and opposite in direction to the reaction producing a couple having a first moment M-1,
c. means 34, 59, 55, 36 to apply an opposite restraining moment M-2 equal in magnitude to the first moment,
d. means 25, 72, 73 to effect control of feed of the drill rod, constructed and arranged to effect that feed of the drill rod is essentially motion of translation at a determinate rate along the longitudinal axis produced, maintaining alignment as the drilling progresses.

2. An apparatus as defined in claim 1, and
e. means 100 to move the drill in a direction opposite to the feed.

3. An apparatus as defined in claim 2 wherein the means

a. applying the force includes
i. a double acting fluid cylinder assembly 25 having, a piston 26 with upper and lower faces, and aligned upper and lower piston rods 27A, 27B secured in the piston and being extensible and retractile through upper and lower cylinder heads 28, 29 providing a

range of motion of the cylinder relative to the piston, the piston rods piston and cylinder having a common axis 30, upper and lower cylinder spaces 34, 35 being defined respectively between the upper and lower cylinder heads and the upper and lower faces of the piston,

ii. means 80 to secure the drill to the cylinder, with the drill rod parallel to the common axis,
iii. a support means 24 having an apex 24.1 and means 60 to secure the upper piston rod at the apex,
iv. means 62 to direct fluid under pressure to the lower cylinder space 35 with the upper cylinder space 34 then being connected to a bleeder pipe 72, the fluid under pressure acting upon the piston tending to move the cylinder downward so applying the force to the drill rod, fluid in the upper cylinder space being free to discharge bleeding off through the bleeder pipe.

4. A combination as defined in claim 3 wherein,

i. the means b to apply the opposite force includes means 36 anchoring a lower end of the lower piston rod in the face.

5. A combination as defined in claim 4, the means anchoring the lower end of the piston rod including,

ii. a universal joint 38 the lower end of the lower piston rod being secured 40 in the universal joint, a stub shaft 39 of the universal joint being secured in a hole 42 of the face.

6. A combination as defined in claim 3, the means d to effect control of feed including,

i. a bleeder valve 73 of the bleeder pipe, rate of bleeding being controlled according to an amount by which the bleeder valve is opened, rate of relative motion of the cylinder to the piston and feed of the drill being a function of the amount by which the bleeder valve is opened.

7. A combination as defined in claim 6, wherein the means e to move the drill in a direction opposite to the feed includes

i. means 62 to direct fluid under pressure to the upper cylinder space 34 the lower cylinder space 35 then being connected to the bleeder pipe, the lower cylinder space being free to discharge bleeding off through the bleeder pipe the fluid under pressure acting upon the piston applying a force urging the cylinder and the drill to move upwards to pull the drill rod from a test hole drilled in the face.

8. A combination as defined in claim 7, the means 80 to secure the drill to the cylinder as aforesaid including,

i. a guide rod 81 having longitudinally spaced holes,
ii. a bracket secured to the cylinder, the bracket having a sleeve 85 having an inside diameter such as to accept the guide rod sliding therewithin,

iii. a detent 87 of the bracket spring urged to enter a hole so as to lock the drill in a selected position with respect to the cylinder, constructed and arranged for the drill rod to be axially movable relative the cylinder throughout a range of travel between the selected positions.

9. A combination as defined in claim 8, and

iv. a longitudinal groove extending between the holes, the detent engaging a sidewall of the groove when the drill is moved axially as aforesaid,

v. a latch pin 89 movable in a latch slot 90 for latching the detent clear of the holes while still engaging the groove sidewall.

10. A combination as defined in claim 7, wherein the means e. to move the drill rod in a direction opposite to the feed further includes,

ii. a pulley 101 secured to the cylinder
iii. a wedge clamp means 114 having an eccentric cam 119 adapted to engage the drill rod, the wedge clamp being movable between upper and lower positions of a range of motion relative to the drill rod,

iv. a cable 108 passing around the pulley and having one end secured to the clamping means with an opposite end secured in a fixed position so that force urging the drill to move as aforesaid is applied by the cable to the wedge clamp means.

11. A combination as defined in claim 10 and wherein,

iv. the wedge clamp has a lever, pivoted between inner and outer ends thereof, the cable being secured to the outer end of the lever,
 v. the eccentric cam being at the inner end of the lever and disengaged from the drill rod until force, applied as aforesaid by the cable to the outer end of the lever, rotates the lever engaging the eccentric cam with the drill rod so that, when the cylinder is moved alternatively upward and downward, each time the cylinder is at a lowest position of its range of motion the eccentric takes a new grip on the drill rod so that it is progressively pulled from the test hole.

12. A combination as defined in claim 3, wherein the means 60 to secure the upper piston rod at the apex of the support means includes,

- a collar 53 having an inside diameter to accept the upper piston rod sliding therethrough,
- legs of the support means being mounted in the collar to swing with respect thereto,
- an upper adjustable stop 55 movable upwards and downwards on the piston rod and being securable to the piston rod bearing against an upper end wall of the collar.

13. A combination as defined in claim 12 with ball and

socket means 47 mounting a leg in the collar.

14. A combination as defined in claim 12, the collar having a short hollow cylindrical sleeve 137 FIG. 10 rotatable of the collar, a leg being mounted in the sleeve to swing with respect thereto.

15. A combination as defined in claim 3, the double-acting fluid piston assembly further including

10 vii. an upper cup seal 32 of flexible material, the seal having a base 32.1 and a sidewall 32.2, the base being secured against an upper face of the piston 26 so as to be concave upwards

15 viii. a similar lower cup seal 32 secured concave downwards to a lower face of the piston, adapted for the sidewalls of the seals to be expanded against the cylinder so as to effect restraint against rotation of the cylinder with respect to the piston.

16. A combination as defined in claim 15, and means 62 to direct fluid under pressure to one cylinder space 34 or 35 with fluid under pressure being in a remaining cylinder space 35 or

20 34, so as to expand the cup seals as aforesaid.

17. An apparatus as defined in claim 1, and means 100 to pull the drill rod from a test hole drilled in the face.
